METER ADAPTER

Kenneth A. Ekstrom, 18275 Weaver Ave.,
Detroit 28, Mich.
Filed Apr. 1, 1960, Ser. No. 19,274
8 Claims. (Cl. 317—111)

This invention relates to electrical adapters and more particularly to a new and improved utility watthour meter socket or adapter adapted to receive an "S"-type watthour meter and hold the same securely therein so that the same, once installed in place, cannot be tampered with. This adapter facilitates the replacement of now obsolete "A"-type watthour meters for indoor or outdoor applications, domestic, commercial and industrial.

Another object of the invention is to provide a new and improved electrical adapter which has a portion thereof slideable to allow access to the screws in the terminal block for the purpose of making electrical connections only when the meter is out of the socket. When the meter is installed in the socket, the slide covers the screws in the terminal block making the connections tamper-proof and movement of the slide is prevented by the rim of the meter. The slide cannot be removed by ordinary means.

The above and other objects of the invention will appear more fully from the following more detailed description and from the drawing, wherein:

FIG. 1 is a side elevation of the device, partly broken away, to show how the meter is attached thereto.

FIG. 2 is a front view of the adapter with meter removed.

FIG. 3 is a front view of the adapter, as shown in FIG. 2 with meter removed and sliding segment moved inwardly to provide means for obtaining access to wire-securing means.

FIG. 4 is a section taken substantially along line 4—4 of FIG. 2.

FIG. 5 is a section taken substantially along line 5—5 of FIG. 2; and

FIG. 6 is a section taken substantially along line 6—6 of FIG. 2.

Referring now to the drawing, the numeral 10 designates the adapter per se which consists of a socket-like structure or shell having a peripheral flange 33, the entire structure being molded of fibre-glass, or the like, having three openings 11 therein through which securing means 30 may be inserted to secure the adapter to a wall, or the like. A plurality of clip-mounting blocks 12, 15, in this or similar location having securing clips 13 mounted thereon, by means of screws 31, FIG. 5, threaded in copper connectors 14, 16, or similar connector arrangements are fastened to blocks 12 and 15. Integrally molded within the adapter is a terminal block portion 18 having longitudinal openings 28 therethrough in which barrels 17 are mounted to receive lead wires 19 which carry current from an outside source through the meter, the same being held securely within the barrel 17 of connectors 14 by means of set screws 22 threaded in barrel 17 accessible through openings 27. When the adapter is secured to a vertical wall or the like the openings 28 extend vertically in a direction parallel to the wall, while the openings 27 are at right angles to the openings 28 and extend horizontally when the adapter is in place.

As shown best in FIGS. 2 and 3 there is provided a slide or sliding member including a sliding segment 21—FIG. 2—showing the same in a closed position and FIG. 3 showing the segment moved to a forward, or what might be termed an open position. In the open position of the slide the segment portion lies wholly within the confines of the peripheral wall of the adapter (FIG. 3),

2

while in the closed position shown in FIG. 2 the segment closes the peripheral wall and forms a part thereof. The base portion of the slide includes a flat portion extending rearwardly from the segmental portion, which segmental portion, as stated above, is complementary to the fixed peripheral portion of the adapter. This segment portion of the device is formed of the same molded fibre-glass as the adapter and is formed so that the base thereof will slide in a recessed portion 24 of terminal block 18. The base portion of the sliding member has formed thereon flange members 23 which in turn ride or slide in longitudinal recesses 24 formed in the sides of terminal block 18. When segment 21 is moved forward its movement is limited by the clips mounted on blocks 15, which act as a stop, and when it is returned to its closed position, curved flange portions 25 on rounded peripheral wall section 32 limit its forward movement. As shown best in FIG. 1, an "S"-type watthour meter 26 is shown having securing members 32' protruding therefrom to engage the securing clips 13 and hold the meter in locked relationship with adapter 10. As long as the meter is in place it will be obvious that its peripheral portion or shell, which lies within the shell of the adapter, effectively prevents the sliding member, including segment 21, 25 from moving inwardly to the position shown in FIG. 3, and thus prevents access to the set screws 22.

The manner in which the device operates is as follows: When it is desired to install an adapter the same is placed against a wall at the spot desired and screws 30 are inserted through openings 11 in the back of the shell and screwed into the wall thereby securing the adapter to same. Sliding segment 21 is then moved forward into the interior of the shell of the adapter 10, as shown in FIG. 3, and set screws 22 are screwed out in barrel 17 through openings 27 to allow lead wires 19 to be threaded through openings 28 so that the same may make contact with copper barrel 17, FIG. 5, after which the set screws 22 are tightened through openings 27 and abut against wires 19 to hold the same securely. Once wires 19 are in place, as shown in FIG. 3, sliding segment 21 is then moved back to its normal position, FIG. 2, and seats on the flange 25 provided on the peripheral section wall 32 of the adapter shell 10, and when in this position set screws 22 are completely covered by the base of the slide making the connections tamper-proof. The device is then ready to receive an "S"-type watthour meter 26, which seats within peripheral wall flange 33, said meter having secured to the back thereof projections 32', which are in alignment with and are adapted to make contact with clips 13, FIGS. 1 and 2, which locks the meter to shell 10. When the meter is in place its peripheral wall, which fits inside of the shell of the adapter, prevents movement of the slide, including segment 21, into the interior of the shell while the base portion of the slide covers the openings 27 leading to the set screw 22, thus rendering them inaccessible as long as the meter remains in place within the adapter shell. The usual electrical sealing band is then placed around the meter and the same is tagged with a conventional meter tag used by most electrical utility companies. When the meter has been locked in place, electric current can then flow through outside lead wires 19 to copper connectors 14 and 16, or other combinations, and then to clips 13 and on through meter contacts 32 to meter 26 for metering.

It will be seen from the above description that there has been disclosed herein a practical indoor or outdoor meter adapter of simple, yet unique construction providing a slide portion which allows access to the screws in the terminal block for the purpose of securing electrical connection only when the meter is out of the

socket and is so formed that when the meter is installed in the socket, the slide covers the screws in the terminal block making the connection tamper-proof. The slide cannot be removed by ordinary means in either the open or closed position.

While I have described and illustrated a satisfactory device that has proven highly successful in practical operation, it will be understood that the invention is not limited to specific constructional details shown and described, but that many changes, variations and modifications may be resorted to without departing from the principles of my invention.

I claim:

1. An adapter of the class described designed to receive and hold in locked relationship an electric metering device, comprising a shell, meter-securing means mounted within said shell, a terminal block portion formed integrally with said shell having openings therein to receive electric wires and means for securing said wires in locked relationship with said terminal block portion, a slideable member including a segment portion and a base portion adapted to be moved forward in said block to allow access to said wire-securing means in said terminal block and to be moved back to its normal or closed position in said block to cover said wire-securing means, said sliding segment portion forming a continuation of the shell wall of the adapter in its rearward or normal position, and the base thereof covering the wire securing means in said terminal block, and said base when the segment is in its forward position being removed from said securing means, allowing access thereto.

2. An adapter of the class described designed to receive and hold in locked relationship an electric metering device having securing means thereon, comprising a shell having a peripheral flange formed integral therewith, clips mounted within said shell, electric contacts connecting said clip members, a terminal block formed integrally with said shell having barrels therein to receive electric wires and means to secure said wires in said barrels, a slideable member including a segment portion and a base portion integral therewith adapted to slide back and forth within said terminal block to allow access to and to cover said wire securing means, said meter securing means being in alignment with said securing clips in said shell so that when said electric wires in said barrels in said terminal block have been locked into place and said sliding segment is returned to its closed position, said meter may be locked to said shell, said sliding segment portion forming a continuation of the shell wall of the adapter in its rearward or normal position, and the base thereof covering the wire securing means in said terminal block, and said base when the segment is in its forward position being removed from said securing means, allowing access thereto.

3. An adapter as set forth in claim 2 in which the terminal block contains a plurality of barrels running longitudinally therethrough to receive electric wires, and a corresponding number of vertical openings leading into said barrels having securing means therein to hold said wires securely in said barrels.

4. A meter adapter of the class described designed to receive and hold in locked relationship an electric metering device having securing means thereon, comprising a shell or socket having a peripheral flange formed

integral therewith, clip-mounting blocks having clips secured thereto mounted in said socket, a terminal block formed integrally with said socket having barrels therein to receive electric wires and means to secure said wires in said barrels, electric contact members connecting said clip mounting block and said barrels, a slideable member including a segment portion and a base portion integral therewith adapted to slide back and forth within said terminal block to allow access to and to cover said wire securing means, said meter securing means being in alignment with said securing clips in said shell or socket so that when said electric wires in said barrels in said terminal block have been locked into place and said sliding segment is returned to its closed position, said meter may be secured to said shell or socket by interlocking said meter-securing means and said clips in said shell or socket making said electrical connections tamper-proof, said sliding segment portion forming a continuation of the shell wall of the adapter in its rearward or normal position, and the base thereof covering the wire securing means in said terminal block, and said base when the segment is in its forward position being removed from said securing means, allowing access thereto.

5. An adapter as set forth in claim 1, wherein the adapter shell is composed of reinforced plastic.

6. An adapter as set forth in claim 1, wherein the terminal block and slide member are composed of reinforced plastic.

7. An adapter as set forth in claim 2, wherein the forward movement of the slide is limited by contact with certain of said clips within the adapter shell and forward movement is wholly prevented when the meter is in place within the adapter.

8. An adapter of the class described designed to receive and hold in locked relationship an electric metering device such adapter comprising a shell, meter-securing means mounted within said shell, a terminal block portion formed integrally with said shell having openings therein to receive electric wires and means for securing said wires in locked relationship with said terminal block portion, a slideable member including a segment portion and a base portion adapted to be moved forward in said block to allow access to said wire-securing means in said terminal block and to be moved back to its normal or closed position in said block to cover said wire-securing means, said sliding segment portion forming a continuation of the shell wall of the adapter in its rearward or normal position, and the base thereof covering the wire securing means in said terminal block, and said base when the segment is in its forward position being removed from said securing means, allowing access thereto, said slide being prevented from forward movement into the shell of the wall of the metering device.

55 when the metering device is assembled with the adapter.
